H. K. Stoner

United States Patent Office.

HENRY K. STONER, OF LANCASTER, PENNSYLVANIA

Letters Patent No. 70,643, dated November 5, 1867.

IMPROVEMENT IN HORSE-RAKES.

The Schedule referred to in these Letters Patent and making part of the same.

TO ALL WHOM IT MAY CONCERN:

Be it known that I, HENRY K. STONER, of Lancaster, in the State of Pennsylvania, have invented a new and improved Mode of Supporting the Iron Teeth on Horse-Rakes; and I do hereby declare that the following is a full, clear, and exact description of the construction and operation of the same, reference being had to the accompanying drawings, making a part of this specification, in which—

Figure 1 shows a cylindrical thimble, A, with an arm, B, a lug, C, with a perforation for the rake-tooth to pass through, set in a line or parallel with the cylinder, and a lug, D, with an eye for a headed screw-bolt, E, set in a line with the projecting arm to which the end of the rake-tooth F is bolted through its eye f. Each tooth is attached to one of these cylindrical holders, which are of the requisite length, and slipped over the horizontal rod across the truck, as other ferrules or teeth-supports in use are held in some cases.

The nature of my invention consists in providing this cylinder or ferrule A with an arm, B, extending at a right angle to it, terminated with a lug or perforated flange, D, or cross-head, C, in order to dispense with the staple-guides, or their equivalent, as they must be of undue length or arrest the tooth in its rise in passing over a stump or other obstruction, and thereby raising the other teeth and dropping the hay, or be seriously injured or broken off; but the tooth so confined in the lug connected with the free action of the cylinder, acts independently on the rod, on which it can turn up to any degree of height without affecting the adjoining teeth, while at the same time there is more steadiness in the tooth, and by its eye it is readily taken off and a new one replaced by means of the bolt and nut E.

The drawings and explanation already given will enable any one skilled in the art to make and use my invention. It is only necessary to add that the arm B' can be extended backwards, with a lug, D', at its end, to which the eye f of the rake-tooth F is bolted and held in the lug c' on the cylinder A'. This arrangement would produce some leverage, and cause the teeth to rise more easily. By attaching the arm on the reverse or opposite side it is essentially the same, and is the plan adopted, as shown in the upper figure.

I am aware that cylindrical holders around which the teeth are fastened are in use, but not provided with an arm with a lug. Arms with a staple or spring attachment to a stationary holder are in use, but these differ substantially in their construction and operation. Such I do not claim.

What I claim as my invention, and desire to secure by Letters Patent, is—

The arrangement and construction of a cylinder, A, with an arm, B, extending from it at right angles, when the rake-tooth F passes through a lug, C, perforated for its reception, and held by a headed bolt or its equivalent, through its eye f in a lug, D, said lugs, arm, and cylinder all of one piece, substantially in the manner shown for the purpose specified.

H. K. STONER.

Witnesses:

W. B. WILEY,

JACOB STAUFFER.
